(57) CLAIM

The ornamental design for a trash bag holder, as shown and described.

DESCRIPTION

FIG. 1 is a perspective view of a trash bag holder showing a new design;

FIG. 2 is a front view of the trash bag holder of FIG. 1;
FIG. 3 is a rear view of the trash bag holder of FIG. 1;
FIG. 4 is a side view of the trash bag holder of FIG. 1;
FIG. 5 is a top view of the trash bag holder of FIG. 1; and,
FIG. 6 is a bottom view of the trash bag holder of FIG. 1.
The components of the display shown in broken lines illustrate portions of the trash bag holder form no part of the claimed design.
